[57] CLAIM

The ornamental design for a retractable hair curling brush or similar article, as shown and described.

DESCRIPTION

FIG. 1 is a perspective view of a retractable curling brush or similar article showing my new design; FIG. 2 is a side elevational view thereof, the broken line depiction of a cord being illustrative of environment only;

FIG. 3 is a front elevational view thereof;

FIG. 4 is a rear elevational view thereof; and

FIG. 5 is a side elevational view of the brush in extended position, it being understood that the continuous rows of teeth are indicated partially by dot-dash lines for ease of illustration.

FIG. 1.

FIG. 2.

FIG. 3.

FIG. 4.

FIG. 5.
